UNITED STATES PATENT OFFICE

2,416,439

VENDING MACHINE

Benjamin W. Fry, University City, Mo., assignor
to National Vendors Inc., St. Louis, Mo., a corpora-
tion of Missouri

Original application May 5, 1941, Serial No.
391,907. Divided and this application July 27,
1944, Serial No. 546,779

5 Claims. (Cl. 312—68)

1

This invention relates to vending machines generally, and with regard to certain more specific features, to vending machines for cigarette packages and the like.

The invention is a division of that disclosed in my United States patent application Serial No. 391,907, filed May 5, 1941, for Vending machine, eventuated as U. S. Patent 2,377,413, dated June 5, 1945; the divisional subject-matter being that directed to means to deliver a match unit or package for each delivery of the article being sold, which in the present embodiment is a package of cigarettes.

Among the several objects of the invention may be noted the provision in a vending machine of the class described having the following characteristics:

A compact, relatively simple, arrangement having a large capacity for match books which does not require pre-loading of matches into the vended packages per se, as heretofore, and matches being carried in the machine in a novel and compact manner.

Another object is the provision of apparatus of the class described which may be easily re-loaded and serviced.

Other objects will be in part obvious and in part pointed out hereinafter.

The invention accordingly comprises the elements and combinations of elements, features of construction, and arrangements of parts which will be exemplified in the structures hereinafter described, and the scope of the application thereof will be indicated in the following claims.

In the accompanying drawings, in which are illustrated several of various possible embodiments,

Fig. 1 is a front elevation on a reduced scale;

Fig. 2 is a side elevation showing in dotted lines a partially removed position of a front panel;

Fig. 3 is a vertical section taken on line 3—3 of Fig. 1;

Fig. 4 is a vertical section taken on line 4—4 of Fig. 1;

Fig. 5 is a vertical section taken on line 5—5 of Fig. 1;

Fig. 6 is a vertical section taken on line 6—6 of Fig. 9;

Fig. 7 is a vertical section taken on line 7—7 of Fig. 9;

Fig. 8 is a vertical section taken on line 8—8 of Fig. 9;

Fig. 9 is a horizontal section taken on line 9—9 of Fig. 1, parts being broken away; and,

Fig. 10 is a fragmentary perspective view of 55

2

a match supply box with the cover partially open, parts being broken away.

Similar reference characters indicate corresponding parts throughout the several views of the drawings.

Inasmuch as a description of much of the mechanical construction of the parent application is not necessary for a complete understanding of the divisional subject-matter herein presented, only that part which is necessary is described.

Referring now more particularly to Figs. 1 and 2, there are shown sides 113 and a back 115 supported upon a base 117. Hooked into the front of the base 117 is a front panel 119 which may pivot forward on a lower hook 154 (Fig. 2), swinging as shown in dash lines in Fig. 2. The front panel carries on it a right-hand coin-return cup 111, a central package receiver 121, and at the left a match-book receiver 123. The cups 111, 121 and 123 are associated with suitable adjacent openings, through the panel 119. A coin inlet is indicated at 125 which receives the necessary pieces. Below the coin receiver 125 is a coin testing and counting unit T which is made along the lines of the testing and counting unit shown in the United States Patent application of Benjamin W. Fry, Serial No. 344,011, filed July 5, 1940, for Coin-controlled apparatus, eventuated as U. S. Patent 2,361,835, dated October 31, 1944. Below the testing and counting unit T is a coin-receiving box 129 for good coins. This coin box receives only 5¢ and 10¢ pieces. All other unwanted coins pass into the coin cup 111. If desired, a coin selector may be employed between receiver 125 and unit T, but this is not shown, being an attachable item of any desired design which may be purchased for the purpose.

At 131 is shown a chute that passes from one end of a horizontal match container 133, to the match-delivery cup 123. Below the match container 133 is a horizontal penny change container 135 which sends pennies from the other end of the machine down a penny chute 137 and through a passage 139 and into the coin cup 111.

Behind the receiver 121 is a flaring delivery trough 141 which receives packages from a series of inner openings 431 across the width of the machine. This is for gravity feed to the central package-delivery cup 121.

The upper portion of the front panel 119 (Fig. 3) slopes back at 143 and is depressed, where it is provided with a long window 145 for viewing one each of various brands of packages in the openings 431, located for display at the upper ends of the individual supply chambers 147.

The manner of releasing these for vending and replacement by successive packages from the supply chambers 147 is fully described in said parent application Serial No. 391,907 (Patent 2,377,413). Above the window 145 are openings 149 from which forwardly extend push buttons 151. The push rods 55 are located under the horizontal penny container as shown in Fig. 3. The individual supply chambers 147 extend vertically and parallel as indicated in Figs. 3 and 6.

The above furnishes enough background construction from the said parent application to locate the match-delivery means which forms the subject of this divisional case. The purpose of the match-delivery means is to supply a book of matches with each cigarette package delivered. The match supply is in a horizontal plane above the horizontal plane of a penny change-maker box shown by numeral 135. This is for maximum saving in space. The match-delivery means has parallel supply columns, none of which becomes empty substantially ahead of the time that any other one becomes empty.

The match supply box 133 is shown in Fig. 10 and consists of a bottom 611 resting upon a cross bar 613 which forms a support. Quick detachable connections are provided at 615. These are gudgeons which may be deposited in open slots 701 cut vertically in supporting members 703. This allows complete removal of the box if desired, or rotation on the gudgeons 615 without removal from the slots 701 in order that the penny box therebelow may be reached. From the bottom 611 are upward dividing walls 617 providing three parallel compartments 619. A hinged cover is shown at 621, notched at 622.

At the left end of the walls 617 (Fig. 10) are flanges 623 for holding the ends of columns of match books 625. Pressing on the other ends of the columns of books are sliding pushers 627 from each of which extend two flexible wires 629. The wires pass over pulleys 631 and then downward by pairs to respective weights 633 sliding in guides 635 on the end of the machine. The wires are positioned on the sides of the wedge-shaped match books and prevent them from spreading laterally (by wedging) and thus prevent jamming.

Normally, the ends of the columns of matches are pushed against tongues 637 of extracting claws 639. Each claw is guided by lateral grooved rollers 641, and by a third roller 645 in groove 643. The rollers 641 and 645 space the claws 639 above a train of gears 647, rotary on an end plate 649. The gear train is driven at a 3:1 speed ratio from the pinion 517 on the end of shaft 515 (Figs. 4 and 7).

Each gear 647 is provided with a drive pin 651 which works in a slot 653 of its respective claw. Thus, upon rotation of the gears, the claws execute vertical reciprocating motion and each is one third of a cycle out of phase with the other, the pins 651 providing such action. Each combination of pin 651 and associated slotted portion of its respective claw member constitutes a Scotch-yoke mechanism.

Upon upward movement of a claw 639, its tongue 637 moves over the first book of matches in the respective column 625, through a notch 622, and upon descent pulls this book down and out of its compartment 619. The lid 621 holds down the match book upon upward motion of the adjacent claw. The respective book moves into position under the tongue 637 by the biasing action of the respective pusher 627. Curved por-

tions 655 of the forward edge of bottom wall 611 are spaced rearward of flanges 623 so as to provide, in effect, delivery slots or outlets at the forward ends of the match book compartments. The lower edges of the flanges 623 are also above the planes of the bottom 611. The forward book in a compartment is pulled down by the respective claw through the respective outlet and projected into chute 131, from whence it moves out to the match delivery cup 123. Each tongue 637 reciprocates from an uppermost point near the uppermost side of an endmost match book but does not move beyond the lower side of any book. This allows each tongue before its downward travel to hook over a book being abstracted without getting under the next endmost book before upward travel of the tongue. If the latter event occurred upward motion of the tongue would be blocked. In view of the elevated position of the lower edge of each flange 623 above bottom 611, each match book is drawn free as its respective claw 639 pulls it down. Matches are successively taken, book by book, from successive columns and delivered to the chute 131 as needed, one book being delivered upon each operation of the machine. By this means, all columns are exhausted at the same rate. Thus a continuous supply of matches is available until all match books are used up, and at the same time space is conserved by having the columns arranged in parallel, along with the four-column penny box in a horizontal plane on top of the machine. The matches are pulled down out of their container and thus no extra head room is required. The cover for the machine indicated at 657 forms part of the front panel 119 and is provided with a lock 659.

No jamming occurs when the match box is empty, because the followers 627 have bevel edges 628 for non-hooking cooperation with the tongues 637. The followers 627 are provided with hooks 626 for holding them in retracted positions while filling (see Figs. 6, 7 and 10).

The gears 647 are operated from the pinion 517 by other parts of the machine. These need not be detailed since this has been done in the parent application and the coordination between them and the remainder of the apparatus is not important to the present divisional subject-matter.

The match container 133 may be removed for loading. The cords 629 allow for complete removal having quick detachable connections 634, and also reduce the friction between the side walls 617 of the box and the columns of matches. The cords thus prevent lateral jamming. Then the box 133 is inserted into the case above the penny box 135, and the front 119 closed. The connections 634 are simply headed pin extensions 660 on the weights 633 under which the cords 629 are removably looped.

The machine has a great capacity for packages, change, matches, all in a very compact space, requiring little head room, since all package delivery is from below. The machine is about 50 inches high. Furthermore, the matches and pennies are laid in horizontal planes (instead of in vertical planes) and are in parallel columns. There is practically no waste space with 70 in the console case. It will be noted in this connection that the means for reciprocating the claws 639 lie within the L shape formed by said claws and the horizontal assembly shown in Fig. 10, the latter forming the match book column container. This leaves a space on the outside

of the L shape for accommodating the cords 629 upon which the weights 633 are suspended.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. In vending apparatus, means to deliver units comprising means to contain a plurality of horizontal columns of said units arranged in a horizontal plane, a plurality of reciprocating means in a common plane normal to the plane of said columns for withdrawing units successively from the respective columns, coordinated Scotch-yoke means operating in a vertical plane and respectively controlling the reciprocating means, a follower member on each column of units at one end thereof, follower cord reaches extending from each follower along two sides of its respective column, guide means at the opposite end of the column adjacent said reciprocating means for guiding said cord reaches, and vertically sliding weights operative in a plane closely adjacent to the plane of operation of said reciprocating means to which said cords are attached, the driving elements of said Scotch-yoke mechanisms being phased at 120° with respect to one another.

2. In vending apparatus, a case, a horizontal package-holding box comprising a horizontal channel for a horizontal column of packages, supporting means for said box within said case, quick detachable means between said supporting means and box allowing tilting of the box to allow for reaching of parts therebelow or complete removal from its supporting means, a follower for the column of packages within the channel, a loop of cord extending from two points on the follower and extending horizontally along the channel, guide means at the front end of the channel for suspending depending portions of the loop, said box being formed with an outlet through which packages may be moved, reciprocating extracting means mounted for movement in said case and operating at said outlet but being free of physical connection with the box whereby the latter may be freely tilted or removed from its supporting means, means in said case for reciprocating said reciprocating means, a suspended weight movable in the case, and quick detachable connections between the cord and weight comprising means on the weight under which the cord is removably looped.

3. In vending apparatus, a case, a horizontal package-holding box comprising a plurality of horizontal channels for horizontal columns of packages, supporting means for said box within the case, quick detachable means between said supporting means and box allowing tilting of the box to allow for reaching of parts therebelow or complete removal from its supporting means, an openable cover over the box allowing access thereto without removal of the box, individual followers for columns of packages within the channels, individual loops of cord extending from two points on each follower and extending horizontally along the channels, guide means at the front ends of the channels for suspending de-

pending portions of the loops, said box being formed with outlets through which packages may be extracted, reciprocating extracting means mounted for movement in said case and cooperating with said outlets but being free of physical connections with the box whereby the latter may be freely tilted or removed from its supporting means, means in said case for reciprocating said reciprocating means, suspended sliding weights movable in the case, and quick detachable connections between the cords and weights comprising means on the weights under which the cords are removably looped.

4. In vending apparatus, a plurality of parallel substantially horizontal channels for holding columns of package units, said channels having delivery outlets at the forward ends thereof, a plurality of slotted reciprocating plates movable in a substantially vertical plane adjacent the forward ends of said channels and providing means for withdrawing units successively from the respective channels through the outlets and dropping them, rotary pin means operating in a substantially vertical plane and respectively controlling with the slots in said plates for controlling them, a follower member in each channel acting against the rearward end of the column of package units therein, follower cords extending from each follower along the sides of the respective column, guide means at the forward ends of said channels adjacent the plates for guiding said cords, and vertically sliding weights to which said cords are attached operative in a plane closely adjacent to the plane of operation of said plates.

5. In vending apparatus, a plurality of parallel substantially horizontal channels for holding columns of package units, said channels having delivery outlets at the forward ends thereof, a plurality of reciprocating members movable in a substantially vertical plane adjacent the forward ends of said channels and providing means for withdrawing units successively from said channels, said channels through the outlets and reciprocating members forming an L-shaped arrangement of parts, rotary means lying within the angle of said L-shaped arrangement for reciprocating said members, a follower member in each channel for the column of package units therein, a loop of cord extending from two points on each follower longitudinally along each channel and vertically outside of said reciprocating members, and means biasing said loops to cause said followers to bias said columns of units toward the forward ends of said channels.
